INVENTOR
BY
Kiedushen & Frankbanka,
ATTORNEYS.

UNITED STATES PATENT OFFICE.

HUGH A. HALL, OF PHILADELPHIA, PENNSYLVANIA.

AUTOMATIC RESTAURANT.

1,389,656.

Specification of Letters Patent. Patented Sept 6, 1921.

Application filed July 31, 1919. Serial No. 314,437.

To all whom it may concern:

Be it known that I, HUGH A. HALL, a citizen of the United States, residing in the city and county of Philadelphia, State of Pennsylvania, have invented a new and useful Automatic Restaurant, of which the following is a specification.

My invention comprehends a novel construction and arrangement of an automatic restaurant, wherein a vending machine of novel construction is employed and wherein the different articles to be vended are conveyed into a position accessible to the intending purchaser in order that he may make a desired selection and, upon depositing in the machine the proper coin or coins, remove the article he has purchased.

It further comprehends a novel construction of an article conveyer, novel means for actuating it, and a novel construction of an article container having a front delivery opening which is provided with a coin-controlled door.

Other novel features of construction and advantage will be more clearly set forth in the detailed description of the embodiment of the invention herein shown.

For the purpose of illustrating my invention, I have shown in the accompanying drawings, forms thereof which are at present preferred by me, since they will give in practice satisfactory and reliable results.

It is to be understood that the various instrumentalities of which my invention consists can be variously arranged and organized and that my invention is not limited to the precise arrangement and organization of these instrumentalities as herein shown and described.

Figure 1 represents a section on line 1—1 of Fig. 2, of an automatic restaurant embodying my invention.

Fig. 2 represents a section on line 2—2 of Fig. 1.

Fig. 3 represents a sectional elevation of another embodiment of my invention.

Fig. 4 represents diagrammatically the coin-controlled mechanism for effecting the unlocking of the front delivery door of an article compartment.

Similar numerals of reference indicate corresponding parts in the figures.

Referring to the drawings:

1 designates a supporting frame-work, the construction of which will vary in accord-

ance with conditions and requirements met with in practice.

The frame work 1 carries at its upper end a top member 2 which extends outwardly beyond the sides or uprights 1 in order to form a table or counter 4, which is divided into individual compartments 5 by means of partitions 6. The sides or doors 3 support at their upper ends a sectional conveyer support 7, which is provided in its body portion with a guide way 8 in which travel the rollers 9 to which are connected the upwardly extending rods 10. These rods pass through overlapping apertured lugs 11 carried by the juxtaposed side walls of article-receiving compartments 12. The rods 10 are provided with collars 13, to which are connected a sprocket chain 14, which is driven by a sprocket wheel 15 mounted on a shaft 16 which is journaled in the conveyer support 7 and in a bracket 17 carried by one of the sides 3. The shaft 16 is provided at its lower end with a worm wheel 18 which meshes with a worm gear 19 on the shaft of the motor 20. This motor is preferably an electric motor, and the arrangement of the gearing is such that a slow travel is imparted to the article-receiving compartments 12.

The conveyer support 7 is preferably made in sections, the lower section being provided with the guide way 8, and the upper section is provided with a slot 22 through which the rods 10 extend. The top member is also provided with a protecting band 23, which surrounds the side portion of the conveyer support. The body portion of the conveyer support and the top section are recessed to form a chamber through which the sprocket chain 14 travels. Each article compartment 12 is provided with a front delivery opening 25 which is closed by means of a door 26, preferably curved, constructed of transparent material, so that the articles to be vended, which have been placed in the article compartments, can be readily seen by the intending purchaser, as such compartments move toward him.

The front delivery door 26 is hinged at one side, as at 27, and a spring 28 is provided, one end of which is fastened to the door, and the other end of which is fixed to the wall of an article receiving compartment, so that the spring retains the door normally in its closed position.

Any desired type of coin-controlled mech-

anism for the front delivery door may be employed, and in order to illustrate one construction of an operative locking mechanism, I have preferred to show it as corresponding in construction and operation with that disclosed in Fig. 8 of my prior patent, No. 1,183,557, dated May 16th, 1916.

Each door is locked by means of a plunger 21 interlocking with it in any desired manner, and as illustrated, each plunger is adapted to move in a stationary guide 29. Each plunger is connected with its respective solenoid plunger 30 of a solenoid 31. The solenoid 31 is provided with a rod 32, which moves in a stationary guide 33, and between this guide and the plunger 30 is interposed a spring 34. One end of the coil of the solenoid is connected to the battery 35 by means of a line 36, and the other end of the coil of the solenoid is connected with the coin chute 39 by means of a line 37. The battery is connected by a line 38 with the coin chute 40 which registers with the coin chute 39.

41 designates a plunger adapted to move into the coin chute 40 and provided with collars 42 between which is located the free end of an arm 43, the other end of which is adjustably connected to the plunger shaft 28 of the solenoid. When the door is locked, the solenoid and its adjuncts appear as in Fig. 4.

44 designates a conveyer top or cover which is carried by posts 45, resting on the 35 conveyer support 7.

The vending mechanism is placed in a building which is provided with a partition 48 through which the conveyer travels. This partition 48 divides the room into a 40 salesroom 46 and a kitchen 47.

The operation of my novel automatic restaurant, will now be readily apparent to those skilled in this art, as follows:—

The attendant in the kitchen places in the 45 article compartments 12, the articles of food which are to be vended. The motor 20 imparts to the conveyer a slow travel so that the intending purchasers who are sitting or standing in front of the compartments 5, 50 can see the articles within an article container as the latter comes into a position accessible to him. If he desires to purchase an article, he places a coin of the proper denomination in the coin slot in the machine. 55 This coin enters the coin chute 39, and passes into the coin chute 40 and is arrested by the plunger 41, thereby closing the circuit and energizing the solenoid 31.

This causes the plunger 30 to move outwardly, and move the locking plunger 21 out of engagement with its respective door 26, against the tension of the spring 34. The purchaser now opens the front delivery door which is unlocked and removes the 65 article purchased from an article container

12. The spring 28 causes the door to close, and the outward movement of the plunger arm 21 moves the plunger 41 out of the path of the coin so that it can descend through the chute 40 into a desired receptacle (not 70 shown).

The article containers during their continuous travel, return to the kitchen where any that are empty can be replenished by the attendant.

75 It will be understood from the foregoing that in accordance with my present invention, I provide a conveyer having a series of individual article receiving compartments, each of such compartments being provided with a coin-controlled front delivery door. The coin is deposited in a coin slot in the front wall of the article container, such slot being of proper dimensions to receive a predetermined coin. The coin passes from the 85 coin slot into the coin chute and effects the unlocking of the door, in the manner already described. The only difference shown in the construction of Figs. 1 and 3 is that in Fig. 3, a plurality of superimposed article compartments are employed, while in Fig. 1, a single line of article receiving compartments are shown, and it is within the scope of my invention, to employ as many superimposed article receiving compartments as may be 90 necessary to meet conditions and requirements.

95 It will now be apparent that I have devised a novel and useful automatic restaurant which embodies the features of advantage enumerated as desirable in the statement of the invention and the above description, and while I have, in the present instance, shown and described a preferred embodiment thereof which will give in practice 100 satisfactory and reliable results, it is to be understood that such embodiment is susceptible of modification in various particulars without departing from the spirit or scope of the invention or sacrificing any of its advantages.

105 Having thus described my invention, what I claim as new and desire to secure by Letters Patent, is:—

115 1. In an automatic restaurant, a conveyer having a series of article receiving compartments, each of which is provided with a coin controlled delivery door, and having juxtaposed walls pivotally connected at their outer ends, and means to actuate said conveyer.

120 2. In an automatic restaurant, a conveyer having a series of article receiving compartments, each of which is provided with a coin controlled delivery door, and having juxtaposed walls pivotally connected at their outer ends, the side walls of a compartment converging rearwardly.

125 3. In an automatic restaurant, a conveyer comprising a series of article receiving com-

- partments having their side walls converging rearwardly, provided with front delivery openings and having coin controlled front delivery doors, the side walls of juxtaposed compartments at their front ends being pivotally connected and having a conveyer chain operatively connected with said compartments, in combination with means to actuate said conveyer chain.
- 5 4. In an automatic restaurant, a support having a guide way therein, rods having members guided in said guide way, a series of article containers carried by said rods, and provided with coin controlled front delivery openings, and means coöoperating with
- 10 said rods to effect the travel of said article container.
5. In an automatic restaurant, a conveyer support having a guide way, rollers in said guide way, rods carried by said rollers, 20 article receiving compartments pivotally mounted at their front ends on said rods, a coin controlled door for each compartment, a sprocket chain connected with said rods to effect the travel of said compartments, and 25 means to actuate said sprocket chain.

HUGH A. HALL.
